UNITED STATES PATENT OFFICE.

EUNICE SUTTON AND SENA M. WARD, OF NEW YORK, N. Y.

GARMENT HANGER.

1,420,890.

Specification of Letters Patent. Patented June 27, 1922.

Application filed July 12, 1921. Serial No. 484,019.

To all whom it may concern:

Be it known that we, EUNICE SUTTON and SENA M. WARD, citizens of the United States, and residents, respectively, of New York city, in the counties of New York and Bronx and State of New York, have invented certain new and useful Improvements in Garment Hangers, of which the following is a specification.

10 This invention relates to garment hangers and more particularly to a hanger especially adapted for supporting ladies' dresses such as evening gowns, for example; and has special reference to the provision of a hanger 15 of this nature constructed and adapted for independently supporting the waist and skirt portions of a dress in an effective manner.

A prime desideratum of our invention 20 comprehends the provision of a garment support for so supporting ladies' dresses as to minimize or eliminate the distorting strains or stresses incident to the present use of the known types of garment hangers, 25 and for so supporting the waist and skirt portions of the dress as to relieve the waist from the weight of the skirt, with the waist hung to assume its natural shape as intended for wear. Ladies' dresses and more par-

30 ticularly those which comprise attached waist and skirt members, are usually supported from the shoulder portions of the waist, the entire weight of both waist and skirt being sustained by these shoulder portions. The weight of the skirt effective on 35 the waist has a pronounced tendency to "pull" on the waist, subjecting the latter to strains and stresses resulting in misshaping or distorting the same, this being especially true in dresses where the skirt is made 40 of relatively heavy material such as serge or jersey silk, and more especially when beaded or provided with spangles, and the waist made of relatively light material such

45 as taffeta silk, satin or chiffon. The weight of both skirt and waist members effective on the shoulder portions subjects the latter to similar distorting strains, and where the shoulder portions comprise shoulder straps 50 or yokes, which are usually made of a delicate fabric such as chiffon material, the yoke portions are subjected to liability of rapid wear and tear. It has therefore been found

desirable to provide a garment hanger especially adapted for supporting ladies' 55 dresses in which the waist or shoulder members or both are relieved of distorting strains and stresses with each member of the garment efficiently supported independently of the other; and the provision of such a 60 garment hanger is a prime object of our invention.

Where the skirt and waist members of the dress are independently supported it has been further found desirable to support the dress member so that not only will 65 any tendency of the waist to assume a distorted appearance be eliminated, but so that any tendency of the waist to be wrinkled to assume undesirable folds and creases will 70 be obviated. The provision of a garment hanger construction in which wrinkling or rumpling of the waist is minimized, with the waist hung to assume its natural shape 75 as worn by the person, is a further prime desideratum of our invention.

The principal objects of our invention therefore include, besides the provision of a garment hanger especially adapted for supporting ladies' dresses, the provision of 80 such a hanger in which the attached waist and skirt members of the dress are independently supported with the weight of a skirt removed from the waist and the shoulder straps or yokes relieved from sustaining the weight of both the skirt and waist, 85 undesirable distortion being obviated; the further provision of such a hanger in which the waist is supported to take and hold its natural shape, undesirable folds and 90 wrinkles being prevented; the further provision of a garment hanger so constructed as to provide efficient means for retaining the shoulder straps or yoke members in position on the hanger against sliding or slipping therefrom and the provision 95 of a garment hanger of exceedingly simple construction, made of inexpensive stock, subject to simplicity of manufacturing operations, the whole providing a low cost unit. 100

To the accomplishment of the foregoing and such other objects as may hereinafter appear, our invention consists in the elements and their relation one to the other, as hereinafter particularly described and 105 sought to be defined in the claims, reference

being had to the accompanying drawings which show a preferred embodiment of our invention, and in which:

5 Figure 1 is a view of our improved hanger, showing the manner of its use,

Figure 2 is a cross sectional view of the same taken on the line 2—2, Figure 1, and

Figure 3 is a view of the hanger drawn to an enlarged scale.

10 Referring to the drawings, the improved hanger comprises a frame generally designated as 10, provided with an upper or shoulder portion or member 11 and a lower or waist portion or member 12, side portions 13 and 14 of the frame spacedly connecting the shoulder and waist members 11 and 12, the frame including the usual hanging or supporting hook 15.

15 The shoulder member 11 is intended for supporting the waist of a dress and more particularly the strap or yoke portions of the waist, the waist member 12 being intended for independently supporting an attached skirt of the dress in a manner as particularly shown in Figures 1 and 2 of the drawings. By independently supporting the waist and skirt portions of the dress the weight of the skirt is removed from the waist and the shoulder straps of the said

20 waist, the strains and stresses which subject the waist and the strap portions to distortion being thereby eliminated, an object especially desired in dresses of the type wherein the skirt member is made of relatively heavy material with the waist member and shoulder portions made of a light and delicate fabric. Independent support for the skirt also obviates and eliminates any possibility of tearing the delicate waist

25 fabric.

30 In order to prevent the waist from being wrinkled or rumpled during support of the same, to eliminate the production of any undesirable folds and creases therein, it is desired that the waist be hung in such a manner as to assume its natural folds and ordinary shape as intended for wear by the user. To this end the shoulder and waist members 11 and 12 are spacedly arranged to correspond to the distance between corresponding members of the human body. With the shoulder and waist members so spacedly arranged the waist may be hung on the hanger, while the skirt is independently supported thereby, so that the waist will take and hold its natural form and shape as is desired for wear, this being clearly indicated in Figures 1 and 2 of the drawings.

35 40 For purposes of efficiently supporting the strap or yoke portions of a dress, means is desired for retaining the strap or yoke portions on the hanger and for preventing the same from sliding or slipping. To this end the hanger is provided with oppositely

45 spaced upturned portions 16 and 17, these upturned portions acting as stop or retaining means for the shoulder straps of the dress, as particularly shown in Figures 1 and 2 of the drawings. For the purpose of 50 efficiently supporting the skirt member from spaced points and for so supporting the skirt as to prevent wrinkling thereof, the waist member 12 is supplied or provided with hook engaging members which may take 55 the form of the spaced loops 18 and 19 respectively, the said loops being intended for the reception of hooks or loop portions, which may be made of braid, and attached to the 60 waist band of the skirt, this manner of supporting the skirt being particularly shown 65 in Figures 1 and 2 of the drawings.

70 For the purpose of adapting the device for general use, as for supporting independent skirt and waist portions, and for supporting sleeved waists as well as sleeveless waists, the hanger is provided with the oppositely arranged outwardly extending portions 20 and 21 for efficiently supporting the shoulders and sleeve members of the 75 waist. To adapt the device to its uses it will be noted that the hanger of our invention simulates the outline of the upper portion of the human trunk.

80 For the purpose of producing an inexpensive unit our hanger is made from a single piece of material bent to the desired configuration. Thus, in the form shown in the drawings the hanger is formed from a single piece of metal wire bent to provide 85 the shoulder member 11, the upturned portions 16 and 17, the outwardly extending portions 20 and 21, side portions 13 and 14, the waist member 12 including the loop elements 18 and 19, one terminal of the metal 90 wire being bent to form the supporting hook 15, the other terminal of the metal wire 22 being either soldered to the bottom of hook portion 15, or twisted thereabout, as shown in Figure 3 of the drawings, the whole providing a unitary and integral garment 95 hanger.

100 The use of our improved hanger will, in the main, be apparent from the above description thereof. It will be further apparent from the foregoing that we have provided a garment hanger especially adapted for use with ladies' dresses in which attached skirt and waist members of a dress may be independently supported in an efficient manner, with the waist member, usually made of delicate fabrics, and its supporting portions such as the shoulder straps or yokes relieved from the distorting weight of the heavier skirt member of the dress, with the 105 waist member so supported and hung on the garment support as to minimize or prevent wrinkling of and undesirable folds in the waist fabric, with the waist being, furthermore, hung to attain its natural shape as de- 110

sired and intended for use. It will be further apparent that the hanger is constructed to be utilizable with sleeved as well as with sleeveless waists and for use with the latter 5 the hanger is provided with means for securely retaining the supporting strips against movement or displacement from the hanger. The hanger is, furthermore, constructed from a single piece of metal bent 10 into the desired configuration, this providing a simple and inexpensive unit.

While we have shown and described our device in the preferred form, it will be obvious that many changes and modifications 15 may be made in the structure disclosed without departing from the spirit of the invention, defined in the following claims.

We claim:

1. A garment hanger comprising a structure providing a shoulder member and a 20 waist member, the said members being relatively spaced a distance corresponding to the distance between corresponding members of the human body, the shoulder member being 25 provided with means for supporting the straps or yokes of a waist and for preventing lateral movement of the yokes from off the said member, the waist member providing means to which a skirt may be hooked 30 to be suspended therefrom; the construction being such that the waist and attached skirt of a dress will be independently supported by the said members, the waist being relieved from the weight of the skirt with the 35 said waist, hung to assume and retain substantially its natural shape.

2. A garment hanger comprising a frame and providing a shoulder member and a waist member, the said members being relatively 40 spaced a distance corresponding to the distance between corresponding members of the human body, the shoulder member being formed to provide spaced upturned portions for retaining the straps or yokes of a 45 waist in position, the waist member being formed to provide spaced loop means to which a skirt may be hooked to be suspended 50 therefrom, the construction being such that the waist and attached skirt of a dress will be independently supported by the said members, the waist being relieved from the weight of the skirt with the said waist hung to assume and retain substantially its natural shape.

55 3. A garment hanger comprising a frame formed from a single piece of metal and, providing a shoulder member and a waist member, the said members being relatively spaced a distance corresponding to the 60 distance between corresponding members of the human body, the members being connected

by integral side portions, the said members and side portions being formed to simulate the outline of the top part of the human trunk, the said shoulder member providing 65 means for supporting the straps or yokes of a waist and for preventing movement of the yokes from off the said member, the waist member providing means to which a skirt may be hooked to be suspended therefrom, the construction being such that the 70 waist of the dress will be relieved from the weight of an attached skirt with the waist hung to assume and retain its natural shape.

4. A garment hanger comprising a frame 75 formed from a single piece of metal wire and providing a substantially linear shoulder member and a substantially linear waist member, the said members being relatively 80 spaced a distance corresponding to the distance between corresponding members of the human body and being arranged in parallel relationship, the said members being connected by integral side portions, the members and the side portions being formed to 85 simulate the outline of the top part of the human trunk, the said shoulder member being formed to provide spaced upturned portions for retaining the straps or yoke of a waist in position, the waist member being 90 formed to provide spaced loop means for supporting a skirt; the construction being such that the waist of a dress will be relieved from the weight of an attached skirt with the 95 waist hung to assume and retain its natural shape.

5. A garment hanger comprising a structure provided with a shoulder member and a waist member, the said members being relatively 100 spaced a distance corresponding to the distance between corresponding members of the human body, the shoulder member being provided with means for supporting the straps or yokes of a waist and for preventing lateral movement of the yokes from off 105 the said member, the waist member providing means to which a skirt may be detachably connected to be suspended therefrom, the said waist member being substantially 110 parallel to the said shoulder member, the construction being such that the waist and attached skirt of a dress will be independently supported by said members, the waist being relieved from the weight of the skirt with the said waist hung to assume and retain 115 substantially its natural shape.

Signed at New York in the county of New York and State of New York this 30th day of June A. D. 1921.
